VARIABLE DELIVERY PUMP

David J. Munroe and John C. McAlvay, Racine,
Wis., assignors to Webster Electric Company,
Racine, Wis., a corporation of Delaware

Application July 23, 1945, Serial No. 606,619

15 Claims. (Cl. 103—41)

1 The present invention relates to variable delivery pumps, and is particularly concerned with pumps of the reciprocating type.

One of the objects of the present invention is the provision of an improved variable delivery pump, the delivery or output of which may be varied continuously or by infinitely small increments from full discharge to zero discharge or no delivery.

Another object of the invention is the provision of a pump of the class described, the amount of delivery of which may be varied while the pump is operating or while the pump is still, with such accuracy that the pump may be made to deliver a full stream or it may be made to deliver liquids drop by drop so that a measured amount of input may be delivered responsive to the turning of a control shaft.

Another object of the invention is the provision of an improved variable delivery pump of the class described which is simple in construction, the parts of which are automatically lubricated and the parts of which are adapted to be economically constructed and used for a long period of time without necessity for repair or replacement.

Another object of the invention is the provision of a variable delivery pump of the class described in which the delivery of the pump may be varied by the movement of certain control valves which are adapted simultaneously to move into a position in which a predetermined amount of the output is bypassed back to the inlet of the pump and the output of the pump is automatically cut off by the same effective amount as the bypass, the cut-off of the output serving to force the fluid being pumped into the bypass channels so as to make the variable delivery positive and accurate.

Other objects and advantages of the invention will be apparent from the following description and the accompanying drawings, in which similar characters of reference indicate similar parts throughout the several views.

Referring to the drawings, of which there are three sheets,

Fig. 1 is a plan view of the pump with the cover plate removed, showing the parts in the position which they assume when the valves are adjusted for full delivery, but the inlet control ports are momentarily out of registry, but are approaching the position of registry for intake into the pumping space below the shuttle block or piston;

Fig. 2 is a view similar to Fig. 1, with the variable delivery controlling valves in the same position, but the trunnion block which controls the

inlet and discharge valves has now reached the position of full registry for intake from the inlet to the lower side of the shuttle block or piston;

Fig. 3 is another similar view, showing the trunnion block in the position of Fig. 1, but the variable delivery valves have been moved from the position of Fig. 1 of full delivery to a different position in which a lesser amount of fluid is delivered, a considerable portion of the fluid being pumped being bypassed back to the inlet port;

Fig. 4 is a view similar to Fig. 3 in that the variable delivery valves are in the same position, but the trunnion block has passed the position of Fig. 2 and is about to be moved out of registry with the inlet ports to the lower side of the shuttle block or piston, as this piston has almost reached the upper limit of its stroke, when its motion will be reversed;

Fig. 5 is a vertical sectional view taken on the plane of the line 5—5 of Fig. 4, looking in the direction of the arrows, showing the body member of the pump, the cover plate, and the intermediate pump housing plate;

Fig. 6 is a transverse sectional view, taken on the plane of the line 6—6 of Fig. 3, looking in the direction of the arrows, showing the inlet and outlet ports in the body member of the pump and the other associated parts at this plane;

Fig. 7 is a view in perspective of the shuttle block or piston member of the pump;

Fig. 8 is a view in perspective of the trunnion block or main valve member of the pump; and

Fig. 9 is a view in perspective of one of the variable delivery valve members of the pump.

Referring to Fig. 5, the present pump preferably includes a supporting body member 11, a cover plate member 12, and an intermediate housing plate 13, all of which may be secured together by suitable screw bolts 14, which pass through the members 12 and 13 and are threaded into the body 11.

The mechanism of the pump is enclosed in the chamber or chambers provided inside the housing plate 13, which are closed on each side by the cover plate 12 or body member 11. This mechanism preferably includes a trunnion block 15, a shuttle block or piston 16, a pair of variable delivery valve members 17, 18, a pivoted lever 19, and shaft 20.

The trunnion block 15, shuttle block 16, and valves 17 and 18 are of the same thickness, but of slightly lesser thickness than the housing plate 13, so that when the trunnion block 15, shuttle block 16, and valves 17 are assembled between the body member 11 and cover plate 12 there is

sufficient clearance between the blocks and valves and the cover plate and body to permit of the free sliding of these blocks and valves, but the clearance is small enough to seal against fluid leakage.

When the pump is used for pumping liquid fuel or other fluids having inherent lubricating qualities, no further lubrication is required other than that which is provided by the fluid being pumped; but when the pump is being used for pumping liquids or fluids having no lubricating qualities, suitable arrangements for the lubrication of the pump should be included.

The body member 11 is preferably provided with a substantially plane face 21 for engaging a similar surface 22, which is located on those parts of the housing plate 13 that are not otherwise apertured and which in particular extend all the way around the border of the housing plate 13, as seen in Figs. 1 to 4.

The body member 11 is also provided with a cylindrical bore 23, serving as a bearing for the shaft 24, which has a cylindrical portion of sufficient length to extend from end to end of the bore 23 and is provided at its inner end with an eccentrically located cylindrical trunnion 25 projecting into the centrally located part of the chamber in the housing plate 13.

Adjacent its lower end in Fig. 5, the body member 11 is also provided with a second through bore 26, serving as a bearing for the variable delivery valve shaft 27, which extends through the bore 26 into the pump chamber, where it passes through a registering bore 28 in the housing plate 13 and terminates in a slot 29 with a noncircular end portion 30, which carries a valve actuating lever 19.

The cover plate 12 may consist of a flat metal plate having a pair of plane surfaces, the innermost of which, 32, forms one of the walls of the pump chamber inside the housing plate 13.

In addition to the foregoing openings, the body member 11 is preferably of sufficient thickness so that it may be provided with an inlet bore 33 and an outlet bore 34 extending into the body member 11 from its opposite edges; and these bores are suitably threaded in their outer ends to receive pipe fittings for connection to pipe for carrying the fluid to and from the pump. The inlet bore 33 communicates with the inner face 21 of the body member 11 through a drilled aperture 35, which is at substantially right angles to the face and which is seen in Figs. 1 to 4 and Fig. 6.

The outlet 34 communicates with the face 21 of the body member 11 by means of a pair of drilled bores 36 and 37, each of which communicates with an elongated slot 38, 39, respectively, located in the face 21 of the body member 11.

The housing plate 13 is provided with the ground faces 22 and 40 located adjacent its edge for engagement with the complementary surfaces on the body member 11 and cover 12. This body plate is pierced by means of a substantially H-shaped aperture, the borders of which are indicated as follows in Fig. 1. 41 indicates the left wall of the aperture and 42 the right wall. The ends of two upper legs of the H shaped aperture are indicated by 43 and 44, while the ends of the two lower legs of the H shaped aperture are indicated by 45 and 46.

What might be called the middle bar of the H shaped aperture is bordered at the top by the plane wall 47 and at the bottom by the plane wall 48. 49 indicates the wall defining the inside

of one upper leg, and 50 the plane wall defining the inside of the other or right upper leg of the H shaped aperture. 51 and 52, respectively, indicate the inner walls of the lower legs of the H shaped aperture in Fig. 1.

Thus it will be observed that the aperture in the housing plate 13 is substantially the same shape as a capital H, but the middle bar portion of the aperture is relatively wide, extending from wall 47 to wall 48.

The two legs of this H shaped aperture are partially filled by the variable delivery valve members 17, 18 (Fig. 1), which are of substantially rectangular shape in cross-section, as seen in Fig. 9, and of sufficient size to slide in the rectangular recess which is located at the right and left sides of the housing plate 13.

The exact shape of these variable delivery valve members will be further described in detail.

20 The rectangular middle portion of the H shaped aperture between the walls 47 and 48 and between the variable delivery valve members 17 and 18 is occupied in part by the shuttle member or piston 16, which is also substantially rectangular in plan and elevation and of such size that it is adapted to slide in engagement with the valve members 17 and 18, the body member 11, and cover 12, from a point adjacent the lower wall 48 to a point adjacent the upper wall 47.

30 The open space above the piston or shuttle member 16 is indicated by 53, and the open space below the shuttle member is indicated by the numeral 54.

35 The shuttle member 16 is thus adapted to act like a piston, but it also is provided with a centrally located through aperture, indicated by the numeral 55, and bounded on the two sides by the walls 56, 57 and above and below by walls 58, 59, each of these walls being a plane surface.

40 The rectangular aperture 53 is adapted to receive the trunnion block 15 for sliding movement, and this trunnion block is shown in Fig. 8. It comprises a metal member of the same thickness as the shuttle block 16 and of sufficient height to 45 slide in engagement with the walls 58, 59. Thus the upper and lower surfaces of the trunnion block 15 are indicated by 60 and 61.

45 The width of this trunnion block 15 is less than the distance between the walls 56, 57 in the aperture 53 of shuttle block 16, thus permitting a 50 reciprocating movement in a horizontal direction, as indicated by the open spaces 62, 63 on each side of the trunnion block 15.

55 The plane side surfaces of this trunnion block are indicated by 64 and 65. The trunnion block 15 has a through cylindrical bore 66 for engaging the eccentric trunnion 25, which, however, is shorter than the thickness of the trunnion block 15 so as to leave the transverse groove 67 on the 60 face 68 of the trunnion block 15 open.

65 The groove 67 connects the spaces 62 and 63 on either side of the trunnion block 15 in the aperture 53 so that the trunnion block effects no pumping action by virtue of its own movement in the aperture 53.

70 The two diagonally opposite corners at the upper right and lower left (Fig. 1) of trunnion block 15 are notched, preferably with substantially rectangular notches 69 and 70, to provide ports that communicate with ports 71 and 72 in the shuttle block or piston 16.

75 It will be noted that the notches 69 and 70 are in registry with the slots 71 and 72 at proper times because both are located in the upper faces

of the trunnion block 15 and shuttle block 16, respectively.

The slots 71 and 72 provide communication between the inner aperture 55 in the shuttle block 16 and the spaces 53 and 54 at either end of this piston 16.

The trunnion block 15 is also provided in the end surfaces 60 and 61 with rectangular slots 73 and 74, which extend all the way through from the front face to the back face of the block 15, as shown in Fig. 8.

These slots 73 and 74 are located to communicate at a proper time with slots 39 and 38 in the body member and with the passageways 75 and 76 in the shuttle block 16. Passageways 75 and 76 each extend outwardly from the central aperture 55 in the shuttle block 16 and laterally in opposite directions with horizontal passageways, indicated at 77, 78, then backwardly at 79 and 80 and outwardly in opposite directions to provide ports 81 and 82.

Passageways 75, 77, 79, 81, and 76, 78, 80 and 82 are in the form of rectangular slots located in the face of the shuttle block 16, as shown in Fig. 7; but the port portions 81, 82 are in the form of rectangular slots which extend from the front to the back of the shuttle block 16, as seen in Fig. 7.

In addition to the foregoing, the shuttle block 16 is provided in its upper right corner on its rear face with a downwardly extending slot 83, which extends laterally, forming a port 84 in the right side 85 of the shuttle block 16. In the lower right corner the rear face of the shuttle block 16 is formed with a rectangular slot 86 extending upwardly and terminating in a port 87 in the left side 88 of the shuttle block 16.

The variable delivery valve members 17 and 18 are similar in construction, but certain slots are reversed in position because of the location of these member on the left and right hand side. The valves 17 and 18 are slotted on the upper surface transversely at 89 and 90, transversely of each of these members, with a rectangular slot.

These slots are located one at one end of the pump and the other at the other end. Thus the slot 89 is adapted to communicate with the space 54 below the piston, and the slot 90 is adapted to communicate with the space 53 above the piston, when the valve members 17 and 18 are suitably adjusted.

The valve members 17 and 18 are substantially rectangular in shape, but are each slotted at their faces at the outer corner to provide a rectangular cut-out 91 and 92 extending the full length of each valve member 17 and 18.

Each valve member 17 and 18 is grooved on its lower surface with transversely and inwardly extending grooves 93, 94, 95, 96. These grooves 93, 94 are joined by a longitudinally extending groove 97, and the grooves 95, 96 are joined by a longitudinally extending groove 98.

When the valve members 17 and 18 are suitably assembled with the other parts of the mechanism, the grooves 93 to 96 form ports, while 65 the grooves 97, 98 form passageways communicating with these ports. Each valve member 17 and 18 has its lower end (Fig. 1) formed with a rectangular cut-out 99 provided with an outwardly projecting cylindrical pin 100.

The pins 100 are adapted to be engaged by the forked ends of the lever 19, which is provided with a suitable slot 101 and spaced legs 102, 103. The pump housing member 13 is grooved at each end to form the rectangular slots 104, 105, which

extend from side to side and provide communication between the open spaces at the ends of the valve members 17 and 18.

The lower one of these slots 105 in Fig. 1 also provides room for the pivoted lever 19. The pump housing member 13 is also slotted in its left wall in Fig. 1 through its entire thickness to form the slot 106, which communicates with a drilled passageway 107 extending from the face 10 of the body member 11 into the intake port 33 in order that excess fluid may be by-passed back to the inlet when the pump is not on full delivery.

The operation of the pump is as follows: In Figs. 1 and 2 the variable delivery valves 17 and 18 are set for full delivery. When the shaft 24 is rotated, as for example in a counterclockwise direction in Fig. 1, the eccentric trunnion 25 will cause the trunnion block 15 to be reciprocated from left to right and upward and downward in a circle.

The size of the aperture 55 in the shuttle block 16 (Fig. 7) is such that the lateral motion of the trunnion block 15 is permitted, while the trunnion block slides in this aperture 55. No pumping takes place between the spaces 62 and 63 at either end of the trunnion block 15 because the open groove 67 permits the fluid to pass freely from left to right, or vice versa, in these places.

As the eccentric trunnion 25 moves the trunnion block 15 up or down in Fig. 1, this trunnion block carries with it the shuttle block or piston 16, which reciprocates in the space between the walls 47 and 48, slidably engaging the sides of the valve members 17 and 18 and causing the spaces 53 and 54 to alternately vary in size or volume.

It is this shuttle block 16 which accomplishes the pumping action.

In Fig. 1 the space 56 is about to be enlarged, and the space 55 is about to be diminished in size, as the eccentric trunnion 25 is on the lower dead center. As the shaft revolves, the cut-out 70 comes into communication with passageway 72, which communicates with lower space 56.

The cut-out 70 communicates with the space 62 and drilled aperture 35 to the inlet 33. Thus, as the space 56 is enlarged by upward movement of the shuttle block or piston 16, fluid is drawn in through the inlet 33, passageway 35, space 62, cut-out 70, and passage 72, to the space 54 below the piston.

The movement of the shuttle block 16 upward from the position of Fig. 1 will cause the port 82 to again register with port 84 and port 88 to register with port 93. When this happens, the fluid in the space 53 above the piston will pass down the passage 83, port 84, to port 93, passage 97, port 94, port 82, passage 86, passage 78, 60 passage 76, slot 74, slot 80, passage 86, to outlet 34.

This action continues until the shuttle block 16 has reached its upper limit of motion and the trunnion 25 is at the upper position opposite to that of Fig. 1.

In Fig. 2 the parts have moved into the position of registry just described, and fluid is being drawn in through the inlet port 33 into the lower space 54 and is being discharged from the upper space 53 out of the outlet port 34.

As the trunnion 25 reaches its uppermost position opposite to that of Fig. 1, the fluid is all driven out of the upper space 53, and the lower space 54 below the piston is entirely filled with fluid.

Then a reversal in the motion of the piston takes place, and shuttle block 16 moves downward. During this motion the cut-out 89 communicates with passageway 71, which communicates with space 63, passage 67, space 62, passageway 35, and inlet 33.

Then on the downward motion of the piston or shuttle block 16, fluid is drawn in through the passages just described, to fill the space 53.

In the meantime fluid is being forced out of the lower space 54 through the following passages: port 81, which has been above port 85, comes down into registry with port 85, port 81 comes into registry with port 86. Also slot 73 in trunnion block 15 comes into registry with 15 port 76.

Then, as the shuttle block 16 passes downward, fluid in the lower space 54, which is now completely full, passes out of the passage 86, port 87, port 95, passage 98, port 96, passage 81, passage 78, passage 77, passage 75, slot 78, and passage 39, passage 37, to outlet 34.

This is the operation of the pump for full delivery.

Referring now to Fig. 3, the variable delivery valve actuating member 18 has been moved to an intermediate position, somewhere between full delivery and no delivery. This moves the valve member 17 down and valve member 18 up from the positions of Fig. 1. The port 89 is thus moved down closer to the space 54, and the port 90 has been moved upward, closer to the space 53.

During full delivery, as shown in Figs. 3 and 4, these ports 89 and 90 are inoperative because they are located beyond the range of operation of the shuttle block 16, so that they never become uncovered.

In the valve position of Fig. 3, however, as the shuttle block 16 moves upward, it soon uncovers the port 89. During that portion of the stroke when the ports 89 and 90 are covered, there will still be full delivery, but during that portion of the stroke when the ports 89 or 90 are uncovered, fluid which is driven from the spaces 52 or 53 will be by-pass fuel back to the inlet port 33, as follows:

Suppose, for example, the shuttle member 16 is moving upward in Fig. 3 until port 90 is covered by shuttle block 16, liquid will pass through port 90 into the passage 92, thence longitudinally to either end of the valve member 18, transversely through slots 104, 105, and past the end of the valve member 17, into passageway 91, thence through slot 106 and bore 107 into the inlet 33. This by-passing action might take place irrespective of any positive cutoff of delivery, as there is a suction applied to the fluid passing out of the space 53 to the inlet, and thence into space 54 during this operation.

However, delivery at this time may also be positively cut off by the action of valves 17 and 18 because ports 93 and 94, for example, have also been moved upward in Fig. 3 from the position of Fig. 1, and port 93 does not come into registry with port 84 nor port 94 into registry with port 82 until this by-passing action has finished and the shuttle block 16 has moved up to cut off the port 90.

As registry between ports 96 and 94 with ports 84 and 82, respectively, is also required for delivery, it will be seen that delivery is also positively cut off while the by-passing action is taking place.

Thus the adjustment of the valve members

17 and 18 may be varied to provide a stepless control of the amount of delivery from full delivery to zero delivery. At zero delivery all of the output would be by-passed back to the inlet.

We desire it to be understood that the shapes and locations of the various passageways may be varied infinitely to accomplish the foregoing results, and we do not wish to be limited to the specific form or shape or location of the parts. For example, it may be that in some embodiments of the invention the trunnion block 15 may be made shorter in a lateral direction in Fig. 1, thus eliminating the necessity for the cut-outs 89 and 10 at the corners thereof.

Also, it may be possible in other embodiments to elongate the slots 38 and 39 and to make the trunnion block 15 shorter in a vertical direction in Fig. 1 to eliminate the necessity for slots 13 and 14. Various other similar changes may be obvious to one skilled in the art.

It will thus be observed that we have invented an improved reciprocating pump, the delivery of which is adapted to be varied continuously without steps from maximum to zero so that this pump may be used for measuring the output of lubricant or liquid fuel, or it may be used to pump gases, suitable provision being made for its lubrication.

When pumping the relatively noncompressible liquids, its delivery may be very accurately predetermined and measured so that such pumps may be used on oil burners, for example, to predetermine the amount of heat by providing a measured amount of fuel, or the amount of lubricant provided to the bearing surfaces of a machine may be accurately measured and supplied by a pump of this character.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim as new and desire to secure by Letters Patent of the United States, is:

1. In a fluid pump of the reciprocating type, the combination of a supporting body provided with a rotating shaft having an eccentric trunnion extending into a pump cavity in said body, with a reciprocating member engaged by said trunnion and adapted to be reciprocated in said cavity by said trunnion, said body being formed with inlet and outlet ports and said reciprocating member being formed with passageways and ports adapted to be alternatively connected to provide communication between the inlet and a pumping space and between the outlet and said pumping space, and adjustable valve means interposed between the outlet port and passageways extending from the pumping space to the outlet port, whereby a predetermined amount of the output may be diverted from the output to effect a predetermined measured discharge of said pump, said body being provided with passageways for conducting the fluid which is diverted from said outlet port back to the inlet of said pump.

2. In a reciprocating pump, the combination of a pump housing provided with a pump chamber defined in part by a pair of opposed parallel plane surfaces, said housing being provided with a bearing for a shaft, said shaft having an eccentric trunnion projecting into said chamber, 75 a trunnion block having a bearing for receiving

said trunnion and of a thickness adapted to be slidably received between said parallel walls, said trunnion being moved in a predetermined orbit by said trunnion, a piston block having an aperture provided with opposed plane surfaces for slidably engaging said trunnion block, said piston block being of a thickness having a sliding fit between the opposed surfaces of said chamber, and said piston block being reciprocated in said chamber by said trunnion block, a pair of valve members, one mounted on each side of said piston block in said chamber, said valve members being movably mounted for movement in the same direction as said piston block, said housing being provided with inlet and outlet ports and with passages and ports communicating with the space between the end of said housing and one end of said piston block, whereby the rotation of said shaft reciprocating said piston block automatically opens valves to the inlet port as said space increases in volume and closes said ports and opens other ports leading to the outlet port from said space when the piston block moves in the opposite direction.

3. In a fluid pump of the reciprocating type, the combination of a supporting body provided with a rotating shaft having an eccentric trunnion extending into a pump cavity in said body, with a reciprocating member engaged by said trunnion and adapted to be reciprocated in said cavity by said trunnion, said body being formed with inlet and outlet ports and said reciprocating member being formed with passageways and ports adapted to be alternatively connected to provide communication between the inlet and a pumping space and between the outlet and said pumping space, and adjustable valve means interposed between the outlet port and passageways extending from the pumping space to the outlet port, whereby a predetermined amount of the output may be diverted from the output to effect a predetermined measured discharge of said pump, said body being provided with pumping spaces at both ends of said reciprocating member, and said valve means controlling passageways from both of said spaces to the outlet.

4. In a fluid pump of the reciprocating type, the combination of a supporting body provided with a rotating shaft having an eccentric trunnion extending into a pump cavity in said body, with a reciprocating member engaged by said trunnion and adapted to be reciprocated in said cavity by said trunnion, said body being formed with inlet and outlet ports and said reciprocating member being formed with passageways and ports adapted to be alternatively connected to provide communication between the inlet and a pumping space and between the outlet and said pumping space, and adjustable valve means interposed between the outlet port and passageways extending from the pumping space to the outlet port, whereby a predetermined amount of the output may be diverted from the output to effect a predetermined measured discharge of said pump, the said body being formed with a substantially rectangular pump chamber and said trunnion being connected to said reciprocating member through the intermediary of a trunnion block adapted to reciprocate in a transverse direction in said chamber.

5. In a fluid pump of the reciprocating type, the combination of a supporting body provided with a rotating shaft having an eccentric trunnion extending into a pump cavity in said body, with a reciprocating member engaged by said trunnion

and adapted to be reciprocated in said cavity by said trunnion, said body being formed with inlet and outlet ports and said reciprocating member being formed with passageways and ports adapted to be alternatively connected to provide communication between the inlet and a pumping space and between the outlet and said pumping space, and adjustable valve means interposed between the outlet port and passageways extending from the pumping space to the outlet port, whereby a predetermined amount of the output may be diverted from the output to effect a predetermined measured discharge of said pump, the said body being formed with a substantially rectangular pump chamber and said trunnion being connected to said reciprocating member through the intermediary of a trunnion block adapted to reciprocate in a transverse direction in said chamber, said trunnion block being provided with

20 passage means for controlling the alternative discharge of fluid from the spaces at the opposite ends of said reciprocating member.

6. In a fluid pump of the reciprocating type, the combination of a supporting body provided with a

25 rotating shaft having an eccentric trunnion extending into a pump cavity in said body, with a reciprocating member engaged by said trunnion and adapted to be reciprocated in said cavity by said trunnion, said body being formed with inlet and outlet ports and said reciprocating member being formed with passageways and ports adapted to be alternatively connected to provide communication between the inlet and a pumping

30 space and between the outlet and said pumping space, and adjustable valve means interposed between the outlet port and passageways extending from the pumping space to the outlet port, whereby a predetermined amount of the output may be diverted from the output to effect a predetermined measured discharge of said pump.

35 said valve means being also adapted to control the cut-off of fluid which is diverted from said discharge port.

7. In a reciprocating pump, the combination of a pump housing provided with a pump chamber

40 defined in part by a pair of opposed parallel plane surfaces, said housing being provided with a bearing for a shaft, said shaft having an eccentric trunnion projecting into said chamber, a trunnion block having a bearing for receiving said trunnion and of a thickness adapted to be slidably received between said parallel walls, said trunnion being moved in a predetermined orbit by said trunnion, a piston block having an aperture provided with

45 opposed plane surfaces for slidably engaging said trunnion block, said piston block being of a thickness having a sliding fit between the opposed surfaces of said chamber, and said piston block being reciprocated in said chamber by said trunnion block, a pair of valve members, one mounted on each side of said piston block in said chamber, said valve members being movably mounted for movement in the same direction as said piston block, said housing being provided with inlet and outlet ports and with passages and ports communicating with the space between the end of said housing and one end of said piston block, whereby the rotation of said shaft reciprocating said piston block automatically opens valves to the inlet

50 port as said space increases in volume and closes said ports and opens other ports leading to the outlet port from said space when the piston block moves in the opposite direction, the said valves and blocks and housing being provided with ports

11

and passages for the utilization of space at each end of said piston block in said housing as a double-acting pump.

8. In a reciprocating pump, the combination of a pump housing provided with a pump chamber defined in part by a pair of opposed parallel plane surfaces, said housing being provided with a bearing for a shaft, said shaft having an eccentric trunnion projecting into said chamber, a trunnion block having a bearing for receiving said trunnion and of a thickness adapted to be slidably received between said parallel walls, said trunnion being moved in a predetermined orbit by said trunnion, a piston block having an aperture provided with opposed plane surfaces for slidably engaging said trunnion block, said piston block being of a thickness having a sliding fit between the opposed surfaces of said chamber, and said piston block being reciprocated in said chamber by said trunnion block, a pair of valve members, one mounted on each side of said piston block in said chamber, said valve members being movably mounted for movement in the same direction as said piston block, said housing being provided with inlet and outlet ports and with passages and ports communicating with the space between the end of said housing and one end of said piston block, whereby the rotation of said shaft reciprocating said piston block automatically opens valves to the inlet port as said space increases in volume and closes said ports and opens other ports leading to the outlet port from said space when the piston block moves in the opposite direction, the said valves and blocks and housing being provided with ports and passages for the utilization of space at each end of said piston block in said housing as a double-acting pump, the said valves having ports and having transfer passages so arranged that the longitudinal movement of said valves effects a cut-off of intake and delivery of fluid pumped by said piston block to adjust the variable delivery of said pump.

9. In a fluid motor device, the combination of a housing having a piston chamber, a piston member mounted in said chamber for reciprocation, said chamber having inlet and outlet ports, and said piston having inlet and outlet conduits provided with piston ports communicating with a cavity therein forming a valve chamber for a reciprocating valve member, a valve member in said valve chamber having conduits and cut-off surfaces for controlling said piston ports, a shaft rotatably mounted on said device, and operative mechanical connections between said shaft and one of said members, whereby the shaft rotates as both members reciprocate.

10. In a fluid motor device, the combination of a housing having a piston chamber, a piston member mounted in said chamber for reciprocation, said chamber having inlet and outlet ports, and said piston having inlet and outlet conduits provided with piston ports communicating with a cavity therein forming a valve chamber for a reciprocating valve member, a valve member in said valve chamber having conduits and cut-off surfaces for controlling said piston ports, a shaft rotatably mounted on said device, and operative mechanical connections between said shaft and one of said members, whereby the shaft rotates as both members reciprocate, and by-pass valve means arranged and constructed with conduits and cut-off surfaces interposed between said piston conduits and said inlet and outlet ports, said valve means being selectively movable to vary gradually the

12

volume of fluid flow through said device by diverting fluid from the inlet and outlet ports to the other end of the piston chamber from the end being used.

5 11. In a fluid motor device, the combination of a housing having a piston chamber, a piston member mounted in said chamber for reciprocation, said chamber having inlet and outlet ports, and said piston having inlet and outlet 10 conduits provided with piston ports communicating with a cavity therein forming a valve chamber for a reciprocating valve member, a valve member in said valve chamber having conduits and cut-off surfaces for controlling said 15 piston ports, a shaft rotatably mounted on said device, and operative mechanical connections between said shaft and one of said members, whereby the shaft rotates as both members reciprocate, said mechanical connections being between said shaft and valve member to cause said valve member to reciprocate while moving in a circular path.

12. In a fluid motor device, the combination of a housing having a piston chamber, a piston member mounted in said chamber for reciprocation, said chamber having inlet and outlet ports, and said piston having inlet and outlet conduits provided with piston ports communicating with a cavity therein forming a valve chamber for a reciprocating valve member, a valve member in said valve chamber having conduits and cut-off surfaces for controlling said piston ports, a shaft rotatably mounted on said device, and operative mechanical connections between said shaft and one of said members, whereby the shaft rotates as both members reciprocate, said piston member and its chamber having plane rectangular sides engaging each other.

13. In a fluid motor device, the combination of a housing having a piston chamber, a piston member mounted in said chamber for reciprocation, said chamber having inlet and outlet ports, and said piston having inlet and outlet conduits provided with piston ports communicating with a cavity therein forming a valve chamber for a reciprocating valve member, a valve member in said valve chamber having conduits and cut-off surfaces for controlling said piston ports, a shaft rotatably mounted on said device, and operative mechanical connections between said shaft and one of said members, whereby the shaft rotates as both members reciprocate, said piston member and its chamber having plane rectangular sides engaging each other, said valve member and its cavity in said piston having plane rectangular sides engaging each other, and said piston and valve member reciprocating in directions extending transversely to each other.

14. In a fluid motor device, the combination of a housing having a piston chamber, a piston member mounted in said chamber for reciprocation, said chamber having inlet and outlet ports, and said piston having inlet and outlet conduits provided with piston ports communicating with a cavity therein forming a valve chamber for a reciprocating valve member, a valve member in said valve chamber having conduits and cut-off surfaces for controlling said piston ports, a shaft rotatably mounted on said device, and operative mechanical connections between said shaft and one of said members, whereby the shaft rotates as both members reciprocate, and by-pass valve means arranged and constructed with conduits and cut-off surfaces interposed between

13

said piston conduits and said inlet and outlet ports, said valve means being selectively movable to vary gradually the volume of fluid flow through said device by diverting fluid from the inlet and outlet ports to the other end of the piston chamber from the end being used, and said mechanical connections being between said shaft and valve member to cause said valve member to reciprocate while moving in a circular path.

15. In a fluid motor device, the combination of a housing having a piston chamber, a piston member mounted in said chamber for reciprocation, said chamber having inlet and outlet ports, and said piston having inlet and outlet conduits provided with piston ports communicating with a cavity therein forming a valve chamber for a reciprocating valve member, a valve member in said valve chamber having conduits and cut-off surfaces for controlling said piston ports, a shaft rotatably mounted on said device, and operative mechanical connections between said shaft and one of said members, whereby the shaft rotates as both members reciprocate, and by-pass valve

14

means arranged and constructed with conduits and cut-off surfaces interposed between said piston conduits and said inlet and outlet ports, said valve means being selectively movable to vary gradually the volume of fluid flow through said device by diverting fluid from the inlet and outlet ports to the other end of the piston chamber from the end being used, and said piston member and its chamber having plane rectangular sides engaging each other.
